ATTORNEYS.

UNITED STATES PATENT OFFICE.

KALLMAN NEWMARK, OF NEW YORK, N. Y.

CIGARETTE CASE.

Application filed March 25, 1924. Serial No. 701,825.

To all whom it may concern:

Be it known that I, KALLMAN NEWMARK, a citizen of the United States, and a resident of the city of New York, borough of Manhattan, in the county and State of New York, have invented a new and Improved Cigarette Case, of which the following is a full, clear, and exact description.

This invention has relation to carrying cases and has particular reference to a novelty cigarette case.

For its principal object the invention contemplates a novelty cigarette case which simulates an automatic pistol in which the stock constituting the cartridge magazine of pistols of this type, in the present instance is designed to serve as a receptacle for receiving the cigarettes, and in which a cover is provided at the upper end of the stock having hinged connection thereto, which cover is provided with means for normally swinging the same to an open position and which cover is further retained in normally closed position by a latch operable by the pivoted trigger to a position to release the cover so that it may be swung to its open position.

As a further object the invention comprehends a novelty cigarette case which is comparatively simple in its construction, inexpensive to manufacture, and which is highly attractive.

With the above recited and other objects in view, the invention resides in the novel construction set forth in the following specification, particularly pointed out in the appended claims and illustrated in the accompanying drawings, it being understood that the right is reserved to embodiments other than those actually illustrated herein to the full extent indicated by the general meaning of the terms in which the claims are expressed.

In the drawings—

Fig. 1 is a perspective view of the cigarette case in closed condition.

Fig. 2 is a vertical longitudinal sectional view therethrough illustrating respectively in full and dotted lines the cover in its closed and opened positions.

Fig. 3 is a sectional plan view taken approximately on the line indicated at 3—3 in Fig. 2.

Fig. 4 is a transverse sectional view taken approximately on the line indicated at 4—4 in Fig. 2.

Referring to the drawings by characters of reference, 10 designates generally a cigarette case body the configuration of which simulates an automatic pistol including a stock 11, a barrel 12 and trigger guard 13, the said case body being preferably, but not necessarily, of a hollow metallic material whereby the stock 11 constitutes a receptacle 14 in which the cigarettes C are adapted to be arranged, the said receptacle being open at its upper end. A cover or closure 15 for the upper open end is hinged thereto as at 16 and is provided with suitable means such as a spring 17 for normally drawing the cover or closure to an open position. At its forward free end the cover is provided with a depending flange 18 formed with a keeper opening 19, which keeper opening is disposed in substantially axial alignment with the barrel 12 when the cover is closed. A trigger 20 is pivoted within the body as at 21 with the manipulating portion 22 thereof extending into the opening defined by the trigger guard 13 and the upper end of said trigger is formed with a rearwardly disposed nose 23 constituting a latch for engaging the keeper opening 19 to hold the cover in closed position against its opening means or spring 17. In order to maintain the nose or latch 23 in engagement with the keeper opening, a spring 23 is provided for swinging the upper end of the trigger rearwardly. The said spring 24 is mounted in a tubular spring seat 25 which constitutes an extension of the bore forming portion 26 of the barrel extending inwardly from the muzzle.

In use and operation of the device, the cigarettes C are loaded into the compartment 14 formed by the stock or grip 11. When it is desired to gain access to the compartment 14, the operator exerts a pull on the trigger 22, swinging the lower exposed portion rearwardly and the upper portion and nose or latch 23 forwardly against the action of the spring 24 to disengage the nose or latch from the keeper opening 19. The cover opening means or spring 17 then functions to swing the cover to its open position illustrated in dotted lines in Fig. 2, whereby the cigarettes may be removed. The device in addition to serving as a novelty and attractive form of cigarette case may be further employed in the capacity of means for warding off attempted hold-ups which are at the present time prevalent.

I claim:

1. A novelty cigarette case comprising a body in the form of an automatic pistol, the grip or stock of which constitutes a compartment for receiving the cigarettes, said grip or stock having a normally closed hinged portion adapted to be opened for gaining access to the interior to introduce or remove the cigarettes, means for normally 5 swinging said hinged portion to an open position, and means simulating a trigger for retaining said hinged portion in its closed position against the action of the opening means.
- 10 2. A novelty cigarette case in the form of an automatic pistol, comprising a stock or

grip portion defining a cigarette receiving compartment and having an open upper end, a cover or closure for said open upper end hingedly attached thereto, means for normally swinging said cover to open position, a flange at the free end of said cover having a keeper opening therein, a pivoted trigger carried by the case having a latching nose, and means for effecting the engagement of 20 said latching nose with the keeper opening when the cover is closed, the said trigger having an exposed portion for effecting the release of the latch nose from the keeper opening. 25

KALLMAN NEWMARK.
